CLAIM

The ornamental design for an inverter and charger integrated power supply, as shown and described.

DESCRIPTION

FIG. 1 is a perspective view of an inverter and charger integrated power supply, showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the drawing views are included for the purpose of illustrating unclaimed portions only, and forms no part of the claimed design.
